LOCOMOTIVE FIRE BOX

Lawrence Richardson, Melrose, Mass.

Application June 2, 1934, Serial No. 728,684

7 Claims. (Cl. 122—58)

This invention relates to improvements in locomotive fireboxes and it consists of the matters hereinafter described and more particularly pointed out in the appended claims.

5 In the conventional type of firebox having inner side sheets, difficulties are encountered in preventing the cracking, breaking through and burning out of said sheets, particularly the lower half adjacent the mud ring. These difficulties 10 result because of the more quiescent state of the water in the bottom of the side water legs of the boiler and also because of the extremely high temperatures which obtain in that part of the firebox especially where the firebox is equipped 15 with the usual refractory arch.

The changes in temperature to which the side sheets of the firebox are subjected when in use, cause an expansion and contraction of the same which leads to their premature breakdown. Such 20 breakdowns often require sheet renewal which is not only costly to make but results in keeping the locomotive out of service for some time, which it is desired to avoid as much as possible.

Many expedients have been tried in an attempt 25 to overcome the difficulties mentioned, with little, if any, success, due either to the inoperativeness of the said expedients or to the excessive costs involved and which made them impractical.

I am aware that corrugating the side sheets 30 of the firebox, either horizontally or perpendicularly, has been attempted. While such a formation permitted the sheet to "breathe" somewhat, i. e. to come and go under temperature changes, the cost was excessive and the making of repairs 35 and in patching the same or the renewal of the bottom end of said sheets is an extremely difficult, if not impossible, matter. I have found that even with such corrugated side sheets, the "breathing" movement is not sufficient to loosen 40 scale or mud which adheres to the water side of the sheets with the result that such sheets soon burned out.

One of the objects of the present invention is to 45 provide a firebox, the bottom portions of the inner side sheets of which are so formed that they will not readily burn out or break through, during periods of use much longer than is now possible with side sheets of any previous design.

Another object of the invention is to provide a 50 firebox having side sheets, formed with areas capable of a greater come and go or breathing movement in the expansion and contraction of the sheets, so that the deposits are loosened on the water side of the sheets, thus insuring a constant water engagement or contact therewith which

prevents adherence of deposits to the side sheets and thus avoiding premature destruction of the side sheet.

A further object of the invention is to provide 5 a firebox, the bottom end of the side sheets of which have longitudinally spaced, substantially vertically disposed, bulge portions therein, which act as flexible diaphragms to loosen deposits on the water side thereof so as to keep them clean and which diaphragms will permit sufficient movement under expansion and contraction as to prevent cracking or breaking through thereof or the pulling away from the associated staybolts.

Still a further object of the invention is to provide 10 a side sheet structure for a firebox which is not only capable of long periods of use but which is economical to make in accordance with present shop practices.

The above mentioned objects of the invention, as well as others, together with the many 20 advantages thereof, will more fully appear as I proceed with my specification.

In the drawing:

Fig. 1 is a longitudinal vertical section through 25 a locomotive firebox embodying the preferred form of the improved side sheets;

Fig. 2 is a horizontal detail sectional view through a part of the firebox on an enlarged scale as taken on the line 2—2 of Fig. 1; and

Fig. 3 is a vertical detail sectional view through 30 a part of the firebox on the scale of Fig. 2, as taken on the line 3—3 of Fig. 1.

Referring now in detail to that embodiment 35 of the invention, illustrated in the accompanying drawing, and especially to Fig. 1 thereof, the fire-box therein shown includes the side sheets 4—4, (only one of which appears) the inside back sheet 5 and the front or flue sheet 6. The various sheets mentioned are connected together 40 at the top by the crown sheet 7 in the usual manner. The bottom end of the flue sheet is formed to provide an inside front throat sheet 8.

The outside back sheet is represented at 9 and said sheet and the inside back sheet are 45 suitably connected by the staybolts 10. Both of these sheets are formed to coact in providing a fuel door opening 11. The outer side sheet is indicated at 13 in Figs. 2 and 3. All of the sheets are connected at the bottom end by a mud ring 14 and coact to provide a front throat 15, a back water leg 16 and side water legs 17, only 50 one of which appears in the drawing. The throat and water legs mentioned all communicate with the water space of the boiler in the conventional manner.

Arch tubes 18 extend from the inside throat sheet 8 to the inside back sheet 5 to support refractory brick to provide the arch 19. The inner and outer side sheets 4 and 13 respectively, 5 are operatively connected by staybolts 20 and the inner and outer front throat sheets are connected by staybolts 21.

It is apparent that the arch 19 is disposed above the firebed on the grate (not shown) and extends upwardly and rearwardly a suitable distance from the inner throat sheet to direct the products of combustion in the front end of the firebox, rearwardly to pass over the arch on their way to the flues secured in the flue sheet 6.

15 Because of the arch, the temperature in the lower part of the firebox is extremely high and there is some variation in temperature throughout the length of the firebox due to the movement of the products of combustion around the end 20 of the arch and due to the fact that the products are in various stages of combustion. The water movement in the bottom of the side water legs is not very vigorous so that the solids in the water tend to accumulate in the bottom of said water legs and there adhere to the water side of the inner side sheets. This materially reduces the cooling action of the water on the inner side sheets and because of the extremely high temperature in that part of the firebox, they burn 30 out and require repair prematurely, relative to other parts of the side sheets.

To overcome such action, the inner side sheets are provided at longitudinally spaced points therealong with vertically elongated diaphragms 35 22 on the fire side of the sheet. They are preferably of a height approximating that height of the sheet most seriously affected by the action above mentioned.

As here shown, each diaphragm begins adjacent the plane of the mud ring and extends upwardly a suitable distance and has curved or rounded top and bottom ends. Each diaphragm also includes a central body portion 23 that is arranged in a plane inwardly of the side sheet 45 proper. Staybolts 20 of increased length serve to support the body portion of each diaphragm. The body portion of each diaphragm merges at its sides and at its ends into the adjacent portions of the associated inner side sheet by side 50 and end marginal portions 24 and 25 of substantially ogee or reversely curved formation.

It is preferable that the width of the diaphragm be less than the distance between alternate vertical rows of staybolts, so that its 55 curved marginal portions merge into the flat part of adjacent portions of the side sheet. It is also pointed out that the central body portion of each vertically elongated diaphragm is substantially flat for the proper securing of the associated staybolts 20 therein.

The curves of the ogee side and top margins of each diaphragm are made on substantial radii, while the curves of the ogee bottom margin of the diaphragm are preferably made on greater 65 radii as indicated at 25a in Fig. 3. This decreases the pocket effect at the bottom end of the diaphragm on the water side thereof and hence, avoids the collection of solids therein to any 70 appreciable extent. Furthermore, this end of the diaphragm, being adjacent the mud ring and being influenced by the attachment of this portion of the sheet thereto, provides an increased flexibility that offsets the stiffness or resistance 75 induced by its position relative to the mud ring.

It will be observed that the central body portion of the diaphragm is spaced a greater distance from the outer side sheet than those portions of the inner side sheets between said diaphragms. This increases the water space in back 5 of each diaphragm so that the water column at that point is of greater depth and is therefore, capable of absorbing heat more effectively and to a greater degree. Thus a turbulence is created in the water space in line with or back of each 10 diaphragm which assists water circulation, and discourages or prevents to a considerable extent, the accumulation of water solids, on the water side of the diaphragms.

The diaphragms also permit and develop a 15 greater come and go or "breathing" movement of the side sheet portions involved, which greater movement breaks up and dislodges any accumulation of water solids on the water side thereof. Thus the diaphragms remain relatively cleaner 20 and will not so quickly burn out.

Again, it is pointed out that with the rounded ends described, the diaphragm can move inwardly and outwardly as a unit as it does not merge at its ends into the adjacent portion of the side 25 sheets with such abruptness as to prevent the movement intended.

Should it ever become necessary to renew the lower half of the side sheet or to make patches in this portion of the side sheets, or should one 30 of the diaphragms require renewal, this would be an easy matter as no complicated matching of sheet and surface parts is required.

The boiler illustrated is that of a large modern locomotive in which the firebox has a length of 35 the order of one hundred fifty inches. In a locomotive of this size I find that three diaphragm portions are very satisfactory. If the firebox were much longer or much shorter a greater or lesser number of diaphragm portions might be 40 required. The number of diaphragm portions should be such that the flexure of the water surface of the side sheets shall be within the elastic limit of the metal but shall exceed the elastic limit of the scale or the adhesion of the 45 scale to the metal.

While in describing the invention, I have referred in detail to the form, arrangement and construction of the parts involved, the same is to be considered only in an illustrative sense so 50 that I do not wish to be limited thereto except as may be specifically set forth in the appended claims.

I claim as my invention:

1. A firebox embodying therein inner and outer 55 side sheets, a substantially vertically arranged, elongated, inwardly bulged diaphragm portion in said inner side sheet having parallel sides and rounded ends that merge into the said sheet by margins of reverse curve cross section, and staybolts connecting said sheets, certain of said staybolts connecting said bulged diaphragm portion to said outer side sheet.

2. A firebox embodying therein inner and outer 65 side sheets, a substantially vertically arranged, elongated, inwardly bulged diaphragm portion in said inner side sheet having parallel sides and rounded ends that merge into the said sheet by margins of reverse curve cross section, and staybolts connecting said sheets, certain of said staybolts connecting said bulged diaphragm portion on its median line to said outer side sheet.

3. A firebox embodying therein inner and outer 70 side sheets, a mud ring to which the bottom end of both sheets are connected, the inner side sheet 75

having a plurality of longitudinally spaced, substantially vertically arranged, elongated diaphragm portions with substantially rounded ends, the rounded bottom end of each diaphragm portion being arranged adjacent the plane of the top of the mud ring, and staybolts connecting said sheets, certain of said staybolts connecting each diaphragm portion to said outer side sheet.

4. A firebox embodying therein inner and outer side sheets, a mud ring to which the bottom ends of both sheets are connected, the inner side sheet having a plurality of longitudinally spaced substantially vertically arranged, elongated diaphragm portions with substantially rounded ends, the rounded bottom end of each diaphragm portion being arranged adjacent the plane of the top of the mud ring, and staybolts connecting said sheets, certain of said staybolts connecting each diaphragm portion to said outer side sheet.

5. A firebox embodying therein inner and outer side sheets, a mud ring to which the bottom ends of both sheets are connected, a fire arch in the firebox between said inner side sheets, a plurality of longitudinally spaced substantially vertically arranged, elongated diaphragm portions in said inner side sheets having substantially rounded ends, the bottom end of each diaphragm portion being arranged adjacent the plane of the top of the mud ring and the top end of certain of said diaphragm portions terminating in

a plane below that of the arch, and staybolts connecting said inner and outer side sheets with certain of said staybolts arranged to connect said diaphragm portions to said outer side sheets.

6. A firebox embodying therein inner and outer side sheets, a mud ring to which the bottom ends of both sheets are connected, vertical rows of staybolts connecting said side sheets, and a substantially vertically arranged, elongated, inwardly bulged diaphragm portion arranged in said inner side sheet between certain of the bolts in alternate rows with certain of the bolts in the intermediate row arranged to connect the median line of said diaphragm portion with said outer side sheet, the said diaphragm portion having substantially parallel sides and having substantially rounded ends.

7. A firebox embodying therein inner and outer side sheets, the inner side sheet having a substantially vertically arranged, elongated diaphragm portion with substantially parallel side margins and rounded top and bottom end margins, the side margins being connected to the body of the inner side sheet by reverse curves of one radius and the bottom end margin being connected to the body by reverse curves of a different radius, and staybolts connecting said sheets with certain of said staybolts arranged to connect said diaphragm portion to said outer side sheets.
